UNITED STATES PATENT OFFICE.

JOHN ZIEGLER BENSON, OF DES MOINES, IOWA.

CURTAIN SWING.

Application filed September 15, 1922. Serial No. 588,458.

To all whom it may concern:

Be it known that I, JOHN Z. BENSON, a citizen of the United States of America, and a resident of Des Moines, in the county 5 of Polk and State of Iowa, have invented a new and Improved Curtain Swing, of which the following is a description.

My invention relates to a curtain hanging means and more especially is intended for 10 use on Ford touring cars and roadsters.

The general object of my invention is to provide a curtain hanging arm adapted to be swingingly mounted whereby the curtain can be swung from its normal position to 15 a position alongside the windshield thereby leaving an open doorway unobstructed by the curtain.

A further object of the invention is to provide for supporting the swingable arm either in position with the curtain disposed 20 at the doorway or at the windshield as well as to provide means for coordinating the curtain supporting arm with the front bow of the top to permit of readily disposing 25 said arm to accord with the folded position of the automobile top.

The manner and means whereby the above and other objects as will appear are accomplished will be readily understood as the 30 description proceeds.

Reference is to be had to the accompanying drawings forming a part of this specification, it being understood that the drawings are merely illustrative of one example 35 of the invention.

Figure 1 is a plan view of my improved curtain supporting means showing the same in use on an automobile illustrated in part;

Figure 2 is a vertical section showing 40 the arm in elevation at the interior of the automobile;

Figure 3 shows the automobile top in transverse section and the curtain supporting arm and curtain disposed against the 45 windshield;

Figure 4 is a face view of the clip for holding the free end or that end of the curtain supporting arm opposite its hinged end;

Figure 5 is an elevation of the clip shown in Figure 4, the curtain supporting arm being shown in transverse section;

Figure 6 is a fragmentary plan view at the hinge end of the curtain supporting 50 arm.

In carrying out my invention in practice

in accordance with the illustrated example an arm 10 preferably stamped from sheet metal is provided at one end with a member 11 hinged to the arm as at 12, said hinge member 11 being secured by a bolt 13 on which it is free to swing in a vertical plane to the front forwardly extending bow A of the automobile at the inner side of the latter to lie adjacent one side arm of said bow. 60 The arm 10 is provided with curtain fasteners 14 whereby to suspend a curtain B of the usual form having isinglass windows b, the curtain at the front end thereof being fastened as usual to the windshield D as at 70 C. The free end of the arm 10 or that end opposite the hinge 12 is curved in hook form as at 15 which in practice is covered by a rubber sleeve, said hook being adapted to engage over the top of the windshield D 75 for supporting the arm and curtain against the windshield when the arm 10 is swung from its normal position across the doorway to a position alongside the windshield D as indicated in dotted lines, Figure 1, and 80 shown in full lines in Figure 3. The rubber sleeve prevents rattling.

On the front upright bow or frame member E of the automobile top I provide a clip 16 secured by bolts 17 and having a fork 85 18 between the members of which fork the outermost curtain fastener 14 is accommodated when the free end of the arm 10 is sprung into engagement with clip 16. Thus, said clip holds the arm 10 firmly in position 90 with the curtain B across the doorway but the arm may be readily detached from said clip and swung to position against the windshield D.

In folding the automobile top the bow A 95 is disengaged from the usual lug F and engaged with the usual lug G below on the adjacent vertical upright bow E. To adapt the curtain arm A to the folding of the automobile top the curtain B is removed, said 100 arm 10 is disengaged from the clip 16 and a pin hole 19 is formed in said arm 10 adapted to receive the pin of the lug F.

When the arm 10 is swung to dispose the curtain adjacent to the windshield D the 105 curtain folds in a manner to prevent damage to the isinglass windows b.

Attention is directed to the fact that the combined windshield engaging hook and handle 15 is formed by extending the metal 110 constituting the arm 10 upwardly and then downwardly. It might be said that the

upward bend in the arm causes the hook to extend upwardly and therefore free from destructive contact with the head or the hat of the occupant of the vehicle. Thus a passenger may sit in the front seat of the vehicle, without possibility of having his or her hat engaged by the hook 15.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claim.

Having thus described my invention, I claim:

A curtain supporting attachment for automobile tops comprising an arm having a

combined attaching and hinge plate hingedly connected thereto, a combined pivot and fastening bolt for pivotally connecting the attaching plate to a bow of the automobile top whereby the arm may swing about a vertical axis or into parallel relation to the bow to which it is connected, the rear portion of said arm being formed with an opening for the reception of a pin by means of which the rear portion of the arm may be secured to a bow of the top when the top is folded, and a supporting clip carried by one of the top bows and having a slot opening out through the upper end thereof, said arm being provided with curtain supporting members, one of which is adapted to extend through the slot in said clip.

JOHN ZIEGLER BENSON.
